UNITED STATES PATENT OFFICE.

ORLAN S. LEE, OF PARSONS, KANSAS.

BALING-MACHINE.

SPECIFICATION forming part of Letters Patent No. 694,166, dated February 25, 1902.

Application filed April 12, 1900. Serial No. 12,653. (No model.)

To all whom it may concern:

Be it known that I, ORLAN S. LEE, a citizen of the United States, residing at Parsons, in the county of Labette, in the State of Kansas, have invented a new and useful Baling-Machine, of which the following is a specification.

My invention relates to self-binding baling-machines; and the object of my invention is to produce a baling-machine which will bale straw as fast as it comes from the thresher or fodder as fast as it comes from the shredder and automatically bind the bales with wire.

My invention comprises, first, novel means for feeding the material into the bale-box; secondly, novel construction and operation of the bale-box; thirdly, novel means for binding the bales with wire; fourthly, novel means for putting the feeding and binding mechanisms alternately into and out of gear with the main driving-gear.

My invention comprises, further, certain novel features of detail construction and arrangement of parts, which will be described hereinafter and pointed out in the claims.

I will proceed to fully describe my invention with reference to the accompanying drawings, in which—

Figure 1 is a rear elevation of the machine. Fig. 2 is a side elevation of the same with several of the gear-wheels omitted for clearness and indicated by dotted lines. Fig. 3 is a sectional view of the devices for feeding and pressing straw into the bale-box. Fig. 4 is a detail view of the feeding parts looking in the direction of arrow in Fig. 3. Fig. 5 is a detail view of the rearward or lower face of the pressing device, the three closing-plates being in section. Fig. 6 is a detail view of the lower end of the same, showing the three closing-plates. Fig. 7 is a detail view of the forward or upper face of the pressing device, the closing-plates being omitted. Fig. 8 is a detail sectional view of the bale-box and its controlling mechanism, showing also a portion of the chute. Fig. 9 is a detail of the bale-box-lowering device. Fig. 10 is an elevation of the gearing at the left-hand side of the machine by which the bale-box pitmen and the binding parts are operated, the chute and parts of the frame

being indicated by dotted lines. Fig. 11 is a sectional detail elevation of the wire-needles and compress in lowered position, the chute 55 in section. Fig. 12 is a sectional detail elevation of the wire-needles and compress in raised position, showing also one of the wire-spools. Fig. 13 is a detail of one of the slotted needle-actuating levers. Fig. 14 is a sectional detail view of the end portion of one of the wire-needles. Fig. 15 is a detail elevation of the same. Fig. 16 is a broken-away elevation of the needles and compress and their actuating mechanism looking in the direction of arrow in Fig. 12. Fig. 17 is a detail side elevation of the wire twisting and cutting mechanism, showing its attachment to the lower end of the chute. Fig. 18 is a detail view of the same, showing the retainer-ratchets. Fig. 19 is a detail plan view of the same, showing the wire retaining and cutting devices. Fig. 20 is an edge view of the plate 172. Fig. 21 is a detail plan view of the wire-twisters, the plate 172 being removed. 75 Fig. 22 is a perspective view of one of the retaining and cutting disks. Fig. 23 is a broken-away sectional view on the line b of Fig. 18, showing one of the retainers engaging a wire. Fig. 24 is a section through one of the twisting-wheels and the adjacent parts. Fig. 25 is a diagram showing the manner in which the wires are placed previous to the formation of a bale. Fig. 26 is a diagram showing the manner in which the wires are depressed by a 80 bale. Fig. 27 is a diagram showing the wire as looped in the retainer and drawn back after the second throw of the needle. Fig. 28 is a diagram showing the wire as cut in two places and two of its ends twisted. Fig. 29 is a detail plan view of the gear-shifting mechanism and the main driving-gear, the main shafts being broken out and the frame-bars broken away. Fig. 30 is a vertical section on the line c of Fig. 29 looking in direction of arrow. Fig. 31 is a vertical section on the line d of Fig. 29 looking in direction of arrow. Fig. 32 is a vertical section on the line e of Fig. 29 looking in direction of arrow. Fig. 33 is a detail view. 95 Fig. 34 is a perspective view of the bale-box in lowered position, showing the parts immediately connected to it and omitting the lifter-bars 79 80 and the lower end of the chute 25.

Fig. 35 is a detached side elevation of the gearing which actuates the wire twisting and cutting devices. Fig. 36 is a diagrammatic view showing one of the wire-twisters in section, 5 the wire as bent around the bale and passing through the twister, and the relative position of the bale-box in dotted lines.

Referring to Figs. 1, 2, 16, and 29, the frame of the machine (designated in general by 1) 10 includes the four corner-uprights secured to the sills, transverse bars between the forward two and rear two uprights, longitudinal bars 2 and 5 at the sides of the top of the frame connecting the uprights, longitudinal bars 3 and 4, between bars 2 and 5, connecting the transverse bars at the top of the frame, rearwardly and downwardly extending looped bars 6, oblique guide-bars 7, secured at their lower ends to the rear sill 1 and near their 15 upper and rear ends to said looped bars 6, and the brackets or hangers 8, (shown most clearly in Fig. 16,) having their upper ends bent inwardly and secured to the top of the chute (hereinafter described) and having 20 their lower ends bent outwardly and secured to the uprights 1 between the corner-uprights at the rear of the machine. The functions of the above guide-bars, looped bars, and brackets or hangers are fully described hereinafter. The main drive-shaft 12, the end of 25 which is shown in Fig. 2 and in plan in Fig. 29, is actuated by the belt-pulley 13 and carries a pinion 14, which drives a gear-wheel 15, Fig. 29. This gear-wheel is mounted on a 30 rotatable shaft 16, which extends the full width of the machine. Shaft 16 is provided near its other end with a gear-wheel 17, which drives gear-wheels 18 and 19, secured on shafts 20 and 21, in the direction of arrows in Fig. 32. 35 (See also Fig. 10.) Near each end of shaft 21 is secured thereto a pinion 22, which engages a gear-wheel 23, keyed to the rotatable feeder-shaft 24.

Referring especially to Figs. 2 and 3, the 40 chute 25, into the mouth 26 of which the straw or other material is introduced, has its upper portion formed in the arc of a circle of which the feeder-shaft 24 is the center, and its central portion is reversely curved in the arc of 45 a circle having as a center the pivot-shaft 38, hereinafter referred to. The upper and lower ends of the chute are secured to the frame 1 in any suitable manner. The upper and rearward wall of the chute 25 has a plurality of 50 slots 27 therein, (see Fig. 1,) through which the feeder-arms 28 are driven as follows: The shaft 24 carries two parallel arms 29, the ends of which are connected by a pair of pull-bars 30. To each of said pull-bars is attached 55 a rod 32 by means of crank-arms 33 of the feeder-arms 28. The ends of bars 32 are provided with rollers 34, which travel in grooves in stationary cams 35, secured to bars 3 and 4 of the frame. Said cams are circular excepting the substantially straight portions, as 60 shown in Fig. 3. The shaft 24 rotates in the direction of the arrow, thereby causing the 65

arms 28 to descend through the chute and carry the straw to a certain point. At this point it is necessary that the arms 28 be raised out of the straw instead of continuing their circular path. This vertical motion is effected by the action of the offsets in cams 35 upon rollers 34, which is to cause a centripetal movement of rods 32 and a consequent change 70 in the angle of said arms, as shown in Fig. 3. After said arms are withdrawn from the chute they reassume the radial position, which they retain until again raised from the chute. The straw is taken up at the point where arms 80 28 leave it by oscillating feeder-prongs 36, playing in slots formed in the lower side of the chute 25. Each of these prongs has a longitudinal slot 37 therein, through which passes the pivot-shaft 38, whose ends are secured in 85 hangers 39, as shown in Fig. 2. Said shaft passes through the side portions of a clip 40, the ends of which are secured to the bottom plate 43 of the press. Another clip 42 is secured to said plate near its upper end. Both 90 of these clips extend around the prongs 36 loosely enough to permit the prongs to slide between said clips and the plate 43, and the function of said clips is to hold the prongs against the plate 43. A cross-bar 44 is secured transversely to the prongs 36 and carries at each end a roller 45. Each of these rollers is guided by a grooved stationary cam 46, one of which is shown in Fig. 3, a sectional view. These cams are secured to oblique braces 1 at the sides of the frame, Fig. 1. On each end of cross-bar 44 the end of a pitman 47 is mounted, the pitmen being actuated by gear-wheels 48 at the sides of the machine. Each gear-wheel 48 is actuated by 105 one of the gears 23 on shaft 24. The prongs 36 are thus oscillated about shaft 38 by the rotation of wheels 48. Each cam 46 contains at its forward end a pivoted switch-block 49 and at its rear end a similar pivoted block 50. These 110 blocks are normally held in the positions shown in Fig. 3 by compression-springs 52. The action of the switch-blocks is as follows: When the prongs 36 near the end of their throw downward through the chute, each 115 roller 45 passes over and depresses block 50 and passes enough farther to release said block, which flies up again and prevents said roller from returning through the upper groove of the cam. The feeder-prongs are 120 now pulled forward out of the chute by the pitmen 47, leaving only the extreme ends or points of said prongs within the slots of the chute. The lower grooves of cams 46, being partly curved in arcs concentric with those of 125 the chute, guide said prongs 36 parallel with the chute until rollers 45 meet the straight inclined portions 53 of the cams. While the rollers traverse these inclines the pitmen 47 are pulling prongs 36 up into the chute, and near the end of the stroke the rollers pass under and raise the forward switch-blocks 49, pass and release them, and then pass back above them. Between the switch-blocks the 130

rollers are supported by the central body portions of the cams 46.

It will be evident from the foregoing description that the feeder-prongs 36 move forward under the chute, are next thrust up into the chute, next move down and back through the chute, then are withdrawn therefrom during their return or forward motion. The upper end of the bottom plate 43 is divided into prongs 54, which register with prongs 36. To prongs 54 are secured curved plates 55 of sufficient width to close the chute-slots through which prongs 36 travel. Plates 55 fit the lower side of the chute and conform thereto in contour, as shown in Fig. 3. (See also Fig. 6.) The straw is fed by the feeder-prongs 36 into the bale-box 56, the construction of which will now be described with reference to Figs. 1, 8, and 34.

The bale-box proper comprises two outer top plates 57, a central top plate 58, supported between plates 57, as hereinafter described, two side plates 59, attached to plates 57 by hinges 60, and an end plate 61, also hinged to plates 57. The bottom of the bale-box is formed by the inclined downward extension 63 of the bottom of the chute 25; but the bale-box is not connected in any manner to said extension nor to the chute itself. Four hangers 64 64', from which the bale-box is hung, have their feet secured to the lateral top plates 57. The upper ends of these hangers terminate in sleeves 66, and through these sleeves extend two straight rods 67, which will be termed "guide-rods" hereinafter, for the reason that they form guides for said sleeves 66, which are actuated by mechanism yet to be described. The upper or forward ends of guide-rods 67 are secured to sleeves which are pivotally mounted on a transverse rotatable shaft 68, to be fully described hereinafter. Between the lower two hangers 64 and parallel therewith are two vertical guide-bars 64^a, having lateral extensions at their upper ends, which are bent downward and secured to the inner faces of said two hangers 64. A bar 69 is mounted slidably between the guide-bars 64^a and has a sleeve 70 at its upper end, through which passes the middle guide-rod 72, having its forward or upper end mounted on the shaft 68 in the same manner as rods 67. The lower portion of each guide-bar 64^a is provided with a longitudinal slot, and through these slots the ends of a pin 81 project, the pin passing also through the bar 69. The ends of this pin 81 are engaged by the forked end of a link 78', the opposite end of which is pivotally connected to an upwardly-extending ear 77', secured to the hinged plate 61 of the bale-box. The bar 69 has a forwardly-projecting boss at its lower end, as shown in Fig. 8, and the inner ends of two toggle-links 78 are pivotally connected to a pin or stud secured in said boss. The outer ends of these toggle-links are pivotally connected, respectively, to ears 77 77, secured to the hinged side plates 59 of the bale-box,

as shown. The middle top plate 58 has a central longitudinal slot 58^a therein, open at its forward or upper end and preferably closed at the lower end. The purpose of this slot is to permit of the upward and forward movement of the ear 77' in a direction parallel to the chute-bottom 63 when the sides of the bale-box are carried in that direction by the rack 75 and gear 73, to be described hereinafter. Each guide-rod 67 has rigidly secured thereto at points lower than the lowest position of sleeves 66 two depending bars 65, which bend inwardly and then downwardly, as shown in Fig. 34, and have their lower ends secured to the sides of the top plate 58, either directly or through the intermediacy of short plates 65, to support the bale-box from the guide-rods 67. The forward ends of the lateral top plates 57 extend beyond the hinged sides 59, and an arched brace 76 has its feet secured to the top of these extended portions. The purpose of this brace is to stiffen the bale-box, and it is necessarily arched in order that it may not collide with the wire twisting and retaining mechanism, which is secured to the lower end of chute 25, as shown in Fig. 17 and described hereinafter. A toothed rack 75 is secured parallel to slide-rods 67 to an extension 64^b of one of the guides 64^a and also to a depending bracket 64', secured to one of the forward or upper hangers 64'. (See Fig. 34.) This rack may also be secured to the arched brace 76. The toothed portion of the rack engages a gear 73, which may be either perfect or mutilated, as shown, keyed on the shaft 68. (See Fig. 8.) A sleeve or boxing 74, having bearings hung from the shaft 68 at the sides of gear 73, holds the rack 75 positively in engagement with said gear.

It will be seen from the foregoing description that the top plate 58 of the bale-box will always be held stationary with respect to the outer slide-rods 67, to which it is secured; but when the rack 75 is moved up and forward by gear 73, as hereinafter described, the bale-box itself will be raised obliquely while being supported by the rods 67, upon which the sleeves 66 will slide. The object of this movement of the bale-box will be explained hereinafter. It will also be seen that if the lower end of the middle guide-rod 72 were raised higher than the corresponding ends of the outer guide-rods 67 the bar 69 would be lifted up between guides 64^a and would raise the inner ends of the three links 78, thereby drawing in their lower ends, which would pull the ears 77 inwardly, and thereby open the plates 59 and 61 outwardly, as shown in Fig. 8. Conversely, a depression of the slide-rod 72 would lower the plunger 69, spread the links 78, and thereby close the plates 59 61 inwardly, as shown in Fig. 34. I also provide for swinging the bale-box bodily out from the chute 25 previous to raising it by the rack 75, and the means I employ for effecting this swinging and for oscillating the middle slide-rod 72 will now be described.

All three of the slide-rods 67 and 72 are os-

cillated by two lifter-bars 79 and 80 and two pairs of pitmen 82 83, the left-hand pair of which is shown in raised position in Fig. 8. Said pair of pitmen have their lower ends 5 mounted on a cranked shaft 84, and the right-hand pitmen are similarly mounted on a cranked shaft 85, symmetrical with shaft 84. The upper ends of the outer pitmen 82 are pivotally connected to the lower lifter-bar 80, 10 which is secured to the lower sides of the outer slide-rods 67. The inner pitmen 83 extend up through slots in lifter-bar 80 and have their upper ends connected to the upper lifter-bar 79, which is centrally secured to the upper side of middle slide-rod 72. The ends of lifter-bar 80 are enlarged and slotted to receive the inclined guides 7, the lower ends of which are secured to bars 6 of the frame 1. (See Figs. 1 and 8.) Each cranked shaft 84 15 85 has secured thereon a pinion 87, which is intermittently rotated by intermittent gears 88 and 101. Said gears are mounted on shafts 132 and 132, respectively. (See Figs. 1 and 8. See also Fig. 10.) The purpose of this 20 construction is to alternately raise and lower the lifter-bars 79 80, and thereby open and close the bale-box, as described heretofore. Integral with gears 88 101 or secured to the 25 sides thereof are stop-cams 89, having circular peripheries, excepting at recessed portions alongside the teeth of said gears. Double-concaved cam-shoes 90 are keyed on shafts 84 85 in alinement with cams 89, which normally engage said shoes and prevent rotation of said 30 shafts, except when the recesses in said stop-cams register with said shoes, when the shoes 90 are free to rotate, and the gears 88 or 101 are then in mesh with pinions 87. Each gear 88 and 101 has one-half the number of teeth 35 provided on each pinion 87, so that pinions are given a half-revolution at a time by gears 88 or 101. The positions in which said shoes and shafts 84 85 are held correspond to the 40 upper and lower positions of lifter-bars 79 and 80. It will thus be seen that when shafts 84 and 85 are rotated the bale-box is alternately swung out by gears 88 and swung in by gears 101. Simultaneously with said 45 swinging out the lifter-bar 79 is raised higher than lifter-bar 80, thereby elevating slide-rod 72 and plunger 69 and opening the bale-box in the manner described heretofore. Conversely, when upper bar 79 is lowered to 50 the level of bar 80 the plunger is depressed, and thereby closes the bale-box.

The initial position of the bale-box 56 when it commences to receive a charge for straw is its highest position, it being supported by the hangers 64 64' and closely embracing the lower portion of the chute 25. The bale-box as it fills with straw is permitted to descend to the position shown by Fig. 8, during which movement the hangers 64 64' slide along the guide-rods 67. It is obvious that 55 during such descent the rack 75 will rotate gear-wheel 73. This backward rotation of said gear is controlled through said rack by

means of the device shown in Fig. 9. The teeth of the ratchet 92 on shaft 68, journaled to frame 1, are normally engaged by shoulder 93 of a pawl 94, which is pivotally secured at 91 to a link 95, the lower end of which is pivoted to frame-bar 1 at 96. A stop-stud 97 on pawl 94 is normally held against said link by spring 98, which thereby 60 presses pawl 94 against the ratchet. When the ratchet is in the position shown, the bale-box 56 is supposed to contain little or no straw; but as straw is accumulated therein by feeder-prongs 36 the pressure against 65 the lower end of the bale-box is transmitted through rack 75, gear 73, and shaft 68 to ratchet 92 and causes a slight rotation of the ratchet. Pawl 94 is thereby forced outward and downward, the spring 98 yielding and 70 permitting the pawl to tilt on pivot 91, and the parts momentarily assume the position shown by dotted lines, thus allowing the ratchet to slip one tooth past the pawl. The next tooth may be caught and held by the 75 pawl, this depending on the amount of pressure of the straw in the bale-box. The slipping of ratchet 92 is repeated until the bale 80 is formed, when the bale-box occupies its lowest position. After the bale is bound and 85 released from the bale-box by the opening thereof the bale-box is raised to starting-point by rack 75, gear 73, shaft 68, and a gear 99 the counterpart of gear 73, secured on the end of shaft 68 opposite from ratchet 92. 90 Gear-wheel 99 is actuated by a mutilated gear 141, which engages it at the proper time to rotate gear 73, and thereby raise the bale-box 56 through rack 75. (See Fig. 10.) While the bale-box descends, the gears 99 95 and 141 are out of engagement with each other, so that the driven gear 99 is then free to revolve. This will be fully understood 100 by reference to Fig. 10. The rotation of the mutilated gear in the direction of the arrow 105 marked thereon rotates gear 99 until the teeth of gear 141 pass the gear 99 and therefore do not engage it. The gear 99 is held in the position to which it is turned by gear 141 by the ratchet 92 and pawl 94, as before 110 described, until the releases of said pawl by 115 pressure within the bale-box.

Referring to Figs. 10, 11, 12, 13, 14, 15, and 16, the compress and the wire-carrying needles 118 will next be described.

When the bale-box 56 is well filled with straw, a portion of the straw in the chute above the bale-box is compressed into the bale-box by compress-ribs 100, (preferably two in number,) which are strongly secured to a cross-bar 102, secured to a pair of compress-arms 103. The inner ends of these arms are pivotally secured to lateral extensions 104 of a plate 105, slidingly held against the lower side of chute 25 by guides 106. Said plate is 109 provided with two pairs of prongs 107, which bridge across an opening 108 in the chute-bottom when said plate is in its forward position. The slots 109 between said prongs ex-

tend back into the body of plate 105, and the extension 63 of the chute-bottom is provided with two slots 110, which register with slots 109. Through these slots the binding-wires extend when carried from the spools 112 to the wire-twisting devices above the chute. Slots 110 are shown in Fig. 1. The ends of compress-bar 102 have wrist-pins 113 thereon, which carry the ends of two connecting-rods 114. The other ends of rods 114 are pivoted to crank-arms 115, which are keyed on the rocker-shaft 116, which is journaled to frame 1 and braces 8. The actuating-arms 117 of the two wire needles 118 are keyed to rocker-shaft 116 at a suitable distance apart. As shown in Fig. 16, a pair of grooved stationary cams 119 are secured to the sides of the frame of the machine, being shown in Figs. 1, 2, 11, 12, and 16. The function of said cams is to guide the compress-ribs 100 by engaging rollers 121 on the ends of wrist-pins 113. When the bale-binding mechanism is set in motion, the compress 100 and needles 118 are in the positions shown by Fig. 11. Rocker-shaft 116 is given about half a turn in the direction of the arrow by the gearing described hereinafter, throwing back the crank-arms 15, which draw back the rods 114, which force the compress-ribs 100 into the chute 25 and then pull them down to the upper end of the bale-box, these movements of the compress being guided by the grooved cams 119. During said downward movement of the compress the needles 118 start and pass up through the chute, passing first between grooves 120 in cross-bar 102, the object of which grooves is to permit needles 118 to pass directly alongside of the compress-ribs 100. The needles thus easily penetrate the looser straw above the bale, and their points describe the arc shown by dotted line until they reach the end of their throw. (Shown by Fig. 12.) The offsets 71 in rocker-shaft 116 are provided in order to permit said shaft to be mounted close to the lower side of the chute and to prevent compress-arms 103 from striking said shaft when the parts are in the position shown by Fig. 12. Shaft 116 may be mounted farther below the chute, in which case the offsets 71 would not be required. When the compress ribs or arms 100 are drawn down, as above described, the slide-plate 105 is also pushed down along the chute by compress-arms 103, which are in turn actuated through rods 114. Said motion of plate 105 withdraws its prongs 107 from across the chute-opening, thereby making room for the compress-ribs 100 and wire-needles 118. The straw having been compressed into a solid bale by compress-ribs 100, as described hereinbefore, and the binding-wires having been secured and cut, as hereinafter described, the wire-needles 118 retreat through the chute, and when they are clear of the chute the compress-ribs 100 are moved up and withdrawn therefrom by a reverse movement of rocker-shaft 116, as will be clearly apparent from reference to Figs. 11 and 12.

Shaft 116 has keyed thereon at the sides of the machine spur-gears 122, which are actuated by sector-gears 123, mounted on short shafts 131 and secured to upwardly-extending levers 124. One of said levers and gears is shown detached in Fig. 13, from which it will be seen that the lever has a longitudinal slot 125 therein, which is engaged by a stud 126, secured to a gear-wheel 127. The gear-wheel 127 and lever 124 are duplicated on the opposite side of the machine, as shown in Fig. 2. The rotation of wheels 127 oscillates levers 124 and gears 123, thereby actuating gears 122, shaft 116, needles 118, and compress-ribs 100. The lever-slots 125 have widened central portions formed on arcs of circles described by studs 126. The object of this construction is to hold levers 124 stationary during two intervals in each rotation of gear-wheels 127. Gears 127 on shafts 129 (see Figs. 1 and 10) are driven by pinions 128 on shaft 20, which shaft is driven intermittently by means to be described hereinafter. The mutilated gear 141, which drives gear 99 on shaft 68, is secured to the shaft 129 of one of the lever-actuating gears 127. (See Figs. 1 and 10.) Gears 130 on short shafts 132 carry the intermittent gears 88 and 101, which rotate the lifter-bar pinions hereinbefore mentioned in connection with the bale-box.

Returning to the binding mechanism, the backs of the wire-needles 118 are provided with grooves 133 for engaging the wires, (see Figs. 14 and 15,) and near the ends of the needles these grooves are spanned by a suitable number of retainers 134. Each needle has a slot 135 near its end, in which slot are mounted two or three grooved antifriction-rollers 136, which prevent the wire from catching on the edges of said slots. The wires are taken from reels or spools 112, threaded through the retainers 134 and through slots 135, and the wire ends are bent back, as shown by dotted line in Fig. 12. One of the wire-spools 112 is shown in this figure. Referring also to Fig. 16, these spools are slipped over horizontal spindles 137, secured to a standard 138. Below each spool 1 is pivotally mounted a tension-lever 139, which may carry a friction-shoe of any preferred kind, and the tension is maintained by springs 140, which may be adjustable, if desired. These tension devices prevent the wires from becoming entangled or kinked.

The manner in which the wires are bound around a bale will be described before describing the retaining, twisting, and cutting devices themselves. Reference is accordingly had to Figs. 25, 26, 27, and 28. In Fig. 25 the twisting mechanism and lower end of the chute 25 are indicated by dotted lines. In Fig. 26 one of the needles 118 is shown, and the bale is shown by cross-hatching. In Figs. 27 and 28 all mechanism is omitted for greater clearness. As the manipulation of both wires is the same, only one of the wires will be mentioned in referring to Figs. 25, 26, 27, 28. It

will be assumed for the purpose of this description that the bale-box (not shown) is in lowered position and is empty. After the wire has been threaded through needle 118, as hereinbefore described, the gearing is put in motion and the needle carries the wire up through the chute, through the wire-twister, and into the wire-retainer, where the end of the wire is caught and held. When the needle retreats, it slides along the wire by means of the slot or eye 135 engaging the wire, and when the needle is down the wire occupies substantially the position shown by Fig. 25. The bale-box will then be raised, and straw will be fed into it to form a bale, as described hereinbefore. When the bale-box is again in lowered position, the wire has been drawn down by the bale, as shown in Fig. 26. The compress-ribs 100 precede the needles into the chute, compressing the bale and holding it compressed. Needle 118 penetrates the loose straw above the bale, carrying the loop of wire above the bale into the retainer, which bites the loop near its end and holds it. The wire is now disposed as shown in Fig. 27. The next operation is the twisting of the two portions of the wire at *t*. These portions are next severed just above the twist, and at the same time the portion of wire extending from the twister to the retainer is cut at *r*, leaving the wire *w* still caught in the retainer, but allowing the two severed pieces to drop out of the way. The needle 118 then retreats through one of the slots 143, the bale is released by the opening of the bale-box, which is run up to starting position, and the above-described operation is repeated.

I will now describe more fully the gearing by which the rock-shaft, pitmen, and other parts are actuated, commencing with the drive-shaft 16 and referring to Figs. 1, 2, 10, and 29.

The drive-shaft 16 carries a gear-wheel 17, which drives gear-wheels 18 and 19, Fig. 29. The shaft 20, on which gear 18 is keyed, carries two pinions 128 of equal diameters at opposite sides of the machine, Figs. 29 and 10. These pinions drive two gear-wheels 127, respectively, mounted on short shafts 129. On one shaft 129 is keyed a segmental gear 141, which engages a segmental gear 99 on a shaft 68, which causes the oblique sliding of the bale-box 56, as described heretofore. Each gear-wheel 127 drives a gear-wheel 130, Fig. 1, said gears 130 being mounted on short shafts 132, respectively. Keyed on each shaft 132 is a double segmental gear 88 101 and a circular stop-cam 89. Keyed on shafts 84, respectively, are two cam-shoes 90, having concave faces which fit the peripheries of cams 89 and are thereby prevented from rotating, excepting once at each rotation of said cams. The rotation of the shoes 89 (with pinions 87) is permitted by recesses in the stop-cams 89, as shown, each recess being large enough to permit one rotation of its shoe 90 while the cam is in rotation. The function of gears 88 101

is to alternately engage pinions 87 on cranked shafts 84 for intermittently rotating said shafts, and thereby operating the bale-box 70 mechanism, as described. Gear-wheels 127 carry pins 126, which oscillate levers 124 and segmental gears 123, which gears drive pinions 122 on rock-shaft 116, to which shaft the wire-needles 118 are secured. (See Figs. 10 75 and 16.)

Referring now to Figs. 17, 18, 19, 21, 22, 23, and 24, the mechanism for twisting and cutting the wires will be described. Fig. 17 shows this mechanism secured to the upper 80 side of the lower end of the chute 25, and it is small enough to permit the arch 76 and the hangers 64' of the bale-box to pass above and straddle it, regardless of the position of the bale-box. The base-plate 142 of the mechanism is firmly secured to the top of the chute, which is drawn in section in Fig. 17 to expose one of the slots which register with slots 143 in plate 142. Through these slots the needles 118 carry the wires into the twisters 90 and the retainers. Rigidly secured to base-plate 142 or integral therewith are two bearings 145 and 146 for the crank-shaft 147, which extends upwardly above the chute and is driven by an intermittent gear, to be described 95 hereinafter. Said shaft has a terminal cranked portion 148, which oscillates the slotted retainer-lever 150, and an oppositely-cranked portion 149, which oscillates the slotted cutter-bar lever 152. Shaft 147 also carries 100 the bevel gear-wheel 153, which drives the twister-pinion 154. The retaining devices include the two plates 155 and 156, secured perpendicularly to base-plate 142, the inner plate 156 being preferably integral with said 105 base-plate. Between plates 155 and 156 on rotatable shafts 157 are mounted the two retainer-disks 158, one of which is shown in perspective by Fig. 22. Each disk is provided with four hooks or prongs 159, and on its face adjacent to plate 156 is secured a four-bladed cutter 160, of which 162 designate the cutter edges. Fig. 22 represents the disk in reverse position from what it would occupy in Fig. 18. The disks 158 are given 110 a step-by-step rotation in the direction of the arrows by ratchets 163 and pawls 164, said pawls being oscillated by lever 150, to which they are pivoted at 161. A guide-bar 165 for said pawls is secured to plate 155, being 115 broken out in Fig. 18. Stop-pawls 167 are provided to prevent backward rotation of ratchets 163 when pawls 164 are wiping said ratchets. Outer plate 155 has two notches 168 in its upper edge, and inner plate 156 has 120 two notches 169 in its upper edge opposite notches 168. The wires being carried into these notches by needles 118, are crimped by a quarter-turn of the disks 158, as shown in Fig. 23, from which it will be seen that the 125 shank of one of the prongs 159 pushes the wire a short distance laterally between itself and the plates 155 156, coming to rest in the position shown. It is evident that a further

quarter-turn of disk 158 will cause one of the blades 160 to sever the wire against the sharp edge of notch 169, the portion of wire being still held between retainer-disk 158 and plate 155. A plate 172 (shown detached in edge view by Fig. 20) is secured to the upper face of base-plate 142 to inclose or cover the gearing described hereinafter to guide the hubs of the twister-wheels and the cutter-bar 179 in the manner to be described. Beneath plate 172 are mounted the twister-wheels 173, the gear-wheel 174, which drives them, and the idle gear-wheels 175. The only function of gears 175 is to reduce the friction between twister-wheels 173 and their bearings. The upper bearings of said twister-wheels are circular openings through plate 172, which openings inclose the enlarged hubs 176 of the twister-wheels. Said circular openings communicate with narrow wire-passages 177, cut through plate 172, (shown in Fig. 19,) which register with slots 143 in plate 142, heretofore described. Twister-wheels 173 are cut by radial wire-slots 178, of a width a little greater than that of the binding-wire used. The lower faces of said wheels are centrally recessed or countersunk, as shown in Fig. 24, a section on line *m m* of Fig. 21 to facilitate the withdrawal of the twisted wires from slot 178. The lower hubs of twister-wheels 173 are seated in annular ribs on plate 142, as shown in Fig. 24, or said hubs may be extended through large circular openings in said plate, the difference being immaterial to the operation of the twisters. As shown in Fig. 24, the inner end of slot 143 registers with the center of the twister-wheel. The radial slots 178 are parallel with each other, as shown in Fig. 21, so that they register simultaneously with passages 177 when rotated to that point by gear-wheel 174, which is secured on shaft 180, driven by pinion 154, and journaled in boss 151. The wires are drawn into said slots 178 in the twisters by needles 118, and when each slot contains two wires, or rather two portions of the same wire, as hereinbefore explained, the bevel gear-wheel 153 is given exactly one rotation. Its diameter is a multiple of the diameter of pinion 154, preferably four times as great. Hence every rotation of the gear-wheel 153 imparts exactly four rotations (in the drawings) to pinion 154, gear-wheel 174, and twister-wheels 173, as said wheels are preferably of equal diameters. When the third rotation of the twisters is completed, the wires are cut off by a cutter-bar 179, (shown in plan in Fig. 19,) from which it will be seen that the cutter-bar is a straight rectangular bar having notches in one of its sides, as described below. During the fourth and final rotation of the twisters the cutter-bar is being drawn back ready for another stroke, as described hereinafter. This cutter-bar is mounted directly upon plate 172, being held thereto and guided by blocks 183, secured to said plate. Cutter-bar 179 is provided with two notches, (most clearly shown in Fig. 19,) each of which has a cutting edge 184. These edges are about the same distance apart as the centers of twister-wheels 173. The hubs 176 of said wheels rise flush with the outer face of plate 172, so that the outer edges of their radial slots 178 form, with edges 184, a pair of shears for severing the wires. The cutter-bar 179 has a lug 186 extending upwardly into the path of the lower end of the oscillating lever 152, which is pivoted on pedestal 145 at 187. (See Fig. 17.) The cutter-bar 179 is pushed in its cutting direction by the stroke of said lever against the lug 186. A spring 188 urges the cutter-bar in the opposite direction, being secured to studs 189 and 190 on the cutter-bar and plate 172, respectively, and its return movement is limited by a stop 179, secured on plate 172. Thus the cutter-bar is reciprocated by the alternate action of lever 152 and spring 188. When the cutter-bar notches register with the radial slots 178 in the twisters, the wires are drawn through them by the needles 118, thence into the retainer-notches 168 and 169, heretofore described. The crank-shaft 147 extends upward and forward to meet a transverse horizontal drive-shaft 192. (Shown in Figs. 1; 2, and 35.) Said drive-shaft carries a bevel gear-wheel 193, which drives crank-shaft 147 by a bevel-gear 194, secured to shaft 147. Shaft 192 has secured to one end thereof a gear-pinion 195, which is rotated intermittently by a short mutilated gear 196 on shaft 192. Gear 196 is concentrically secured to one of gears 127 and is revolved thereby. It occupies a position corresponding to that of mutilated gear 141 on the opposite side of the machine. (See Fig. 29.) Keyed to the shaft 192 of gear 196 and concentric therewith is a stop-cam 197, whose periphery is circular, excepting a recessed portion opposite the teeth of the gear 196. A double-concaved shoe 198 is keyed to said shaft in a position to slidily engage the normal periphery of cam 197, and thereby prevent accidental rotation of pinion 195 and shafts 192 and 147, operating the wire-twisters. When the gear 196 meets pinion 195, the recess in cam 197 permits the shoe 198 to rotate with said pinion. Thus the wire-twisters 173 are operated once at each rotation of main gear 127 and gear 196. From the preceding description and from reference to Figs. 25, 26, 27, and 28 the wire twisting and cutting operations may be fully understood. The wires leading from around the bale are drawn through twister-slots 178 into the retaining devices, by which they are held during three revolutions of the twister-wheels 173. The ends of the wire-needles 118, in order to carry the wires into the retainers, pass between the oscillating pawls 164 and the lever 150. (See Fig. 18.) During the fourth and final revolution of said twisters the wires are cut by rotary cutters 160, after

which the twisted ends of the wires are pulled down out of the twisters by the fall of the bale released by the opening of the bale-box.

It is evident that the bale-binding mechanism does not act continuously, though the main drive-shaft's rotation is continuous. I will next describe my improved and novel device for throwing the feeding mechanism and the binding mechanism alternately into gear with the main driving gear.

Referring especially to Figs. 29 and 31, the middle transverse shaft 16, which is continuously rotated by gear 15, carries the intermediate drive-wheel 17. Said wheel 17 drives the two gear-wheels 18 and 19, of equal diameters, though not necessarily of the same diameter as gear 17. Wheels 18 and 19 are not keyed to their shafts 20 and 21, but are caused periodically to engage said shafts by the means to be described. As shown most clearly in Fig. 31, a section on line of Fig. 29, shaft 20, has secured thereto a radial arm 200, to the outer end of which is pivoted a forked arm 202, urged inwardly by a spring 204, secured to a lug on arm 200. Arm 202 is provided with a detent 206, the inner face of which is curved in an arc having pivot 191 as a center. An antifriction-roller 208 is secured to the web or one of the spokes of gear-wheel 18, and is adapted to engage detent 206. A radial arm 201 and a pivoted detent-arm 203 are likewise secured on shaft 21, and wheel 19 carries an antifriction-roller 207, adapted to engage detent 205. An oscillating beam or lever 209 is pivotally secured at 210 to a standard 212, which is secured to frame 1. Beam 209 carries at one end an antifriction-roller 214 and at the other end an antifriction-roller 215. The upper face of beam 209 is grooved or channeled longitudinally to form a trackway for a roller 213, which is run to and fro upon said track by a rod 216, pivotally connected with the cranked shaft 217. The spindle of roller 213 is journaled in the end of rod 216 and also in the lower end of a rod 218, which passes upward through a slot in the overhanging arm 219 of standard 212. In Fig. 29 the overhanging arm 219 and rod 218 are omitted in order to expose other parts. Rod 218 is inclosed by a spiral compression-spring 220, which is confined between the arm 219 and a collar on rod 218. Spring 220 thus keeps roller 213 pressed against the beam 209, and said beam is tilted one way or the other, according to which side of its center the roller 213 rests on. This depends in turn on the position of cranked shaft 217, pivoted at 221 and at 222. (See Figs. 29 and 32.) Secured on one of the axial portions of cranked shaft 217 is a depending arm 223, having an upward extension 224. Pivotal mounted on the same shaft, in alignment with arm 223, is another depending arm 225, having an upward extension 226. A compression-spring 227, interposed between said upper ends, holds said arms normally together, as shown in Fig. 30. An eccentric

rod 228, whose outer portion is supported by the hanging guide 229, has a catch 230 pivoted thereto at 231. This catch carries a depending box or stirrup 232, the sides of which straddle rod 228. A compression-spring 233 is secured within box 232, as shown by Fig. 33, a section on line X X of Fig. 30. Rod 228 is oscillated by the eccentric 234. (Shown most plainly in Fig. 10.) When rod 228 moves forward, (to the right in Fig. 30,) the catch 230 pushes the lower end of arm 223 before it until it is released from said arm by the ascent of said arm on the other side of shaft 217. Said shaft is thus rocked, throwing its cranked portion, rod 216, and roller 213 to the position shown in Fig. 32. When the eccentric-rod pulls catch 230 back, (to the left,) the catch does not engage arm 223, which has been raised by said catch to a point above the return-path of the catch. The reverse throw of cranked shaft 217 is effected by a pull-rod 235, carrying a collar 236, which engages a depending lever 237, secured to said cranked shaft. Rod 235 slides through an eye in the lower end of lever 237, and when it moves in the direction of arrow in Fig. 32 the collar 236 pulls said lever to the left, thereby returning roller 213 to the position shown in Fig. 31. The rear lower end of pull-rod 235 is secured to one of the hangers of bale-box 56, and it is the descent of the bale-box that draws rod 235 back through the eye of lever 237. The collar 236 is set at such a point on rod 235 that when the bale-box reaches its lowest position the collar will have pulled lever 237 to the end of its stroke. A bridge-piece 238, having stops 239 for shaft 217, has its legs secured to frame-bar 3, and each of said legs has a slotted guide-portion 238' for the arms of a double dog-bar 240, pivoted at 241. Said bar has a central upwardly-extending arm 242, which is connected to the adjacent arm of cranked shaft 217 by a spiral spring 243. When shaft 217 moves rearwardly, spring 243 is compressed and pushes arm 242, thereby depressing dog 244. When shaft 217 moves forward, the spring is extended and pulls arm 242, thereby depressing the other dog 245. Spring 243 is employed for the reason that the throw of crank-shaft 217 is greater than that of arm 242. When dog 244 is depressed, it engages a ratchet 246, secured to shaft 20, thereby preventing backward rotation of said shaft. Dog 245, when depressed, engages a ratchet 247 for the same purpose with respect to shaft 21. The shaft 20 carries the pinions 128, which drive the binding mechanism. The shaft 21 carries the pinions 22, which drive the feeding and pressing mechanism. Consequently the binding mechanism will be started and the feeding mechanism stopped every time that roller 215 descends, so as to engage the end of detent-arm 203. Said end portion rides up on the roller, as shown in Fig. 31, thereby lifting its detent 205 up from in front of roller 207, which roller continues its revolution; but shaft 21

comes to rest. At the same time the roller 214 on the opposite end of beam 209 is raised to the position shown, thereby releasing detent 206 and permitting it to fall into the path of roller 208, which engages it and thereby starts shaft 20. The eccentric 234 is so adjusted on its shaft that the eccentric-rod 228 throws the binding parts (including the eccentric itself) out of gear just after the bale-box 56 has been raised and closed. When the next bale has lowered the bale-box to its lowest point, the pull-rod 235, attached thereto, throws the binding mechanism into gear, as described above. (See also Fig. 1.)

15 A recapitulation of the operations performed by the different parts of the machine in their consecutive order would be as follows: The material is fed into the mouth 26 of the chute 25 and is carried through a part 20 thereof by the arms 28, from which it is taken by the prongs 36 and carried farther down through the chute to a point where it is engaged by the pressing-arms 100 and pressed into the bale-box 56, which is raised to its 25 highest position after discharging the preceding bale. While the bale-box is being filled, it is lowered intermittently by the pressure and weight of the material causing the ratchet 92 to slip, and thereby permit movement of the rack 75. When the bale-box descends to its lowest position, the bale is formed therein and rests upon the two binding-wires, the ends of which have previously been carried to the retaining devices by the 35 needles 118. The needles now carry the looped wires up around the bale, through the twisters, into the retaining and cutting devices. The twisters tie or twist the wires close to the bale, and the wires are immediately severed above the twists by the cutter-bar 179 and severed in the retainers by the rotary cutters 160. The needles 118 and press-arms 100 are retracted by movement of rock-shaft 116, and plate 105 slides up to close 40 the opening 108 in the bottom of the chute. The bale-box 56 is swung out and opened by gears 88, acting through the mechanism described hereinbefore. This releases the bound bale, which falls off the extension 63 45 of the chute-bottom. The bale-box 56 is then raised obliquely by rack 75 and gears 73 99 141, &c., then swung in against the chute and close by gears 101, which follow gears 88 and act upon the same mechanism. The eccentric-rod 228 next throws the binding mechanism out of gear by acting on the gear-shifting mechanism, as described, and at the same time it throws the feed-arm gears 23 and 48 into gear with the main driving-gear actuated 50 through shaft 16, after which the eccentric stops. The feeder-arms 28 and the prongs 36 operate until the bale-box reaches its lowest position, at which time the rod 235, secured to the bale-box, throws gears 23 and 48 55 out of gear and the binding mechanism and eccentric into gear.

Having now fully described my invention,

what I claim as new, and desire to secure by Letters Patent of the United States, is—

1. In a baling-machine, the combination, 70 with a curved chute, of a transverse rotatable shaft, means for driving said shaft, arms carried thereby, a transverse rod carried by said arms parallel to said shaft, crank-arms mounted pivotally on said rod, a rod secured 75 pivotally to said crank-arms parallel to said shaft, feed-arms mounted on said rod and extending into the chute through slots therein, and stationary grooved guides for the ends of said rod, substantially as and for the purpose 80 described.

2. In a baling-machine, the combination, with a curved chute having longitudinal slots in its upper side, of a transverse rotatable shaft above the chute, means for driving said 85 shaft, arms carried by said shaft, a transverse rod carried by said arms, crank-arms mounted pivotally on said rod, a rod pivotally secured to said crank-arms and having a roller on each of its ends, feed-arms mounted 90 on said rod and rigidly secured to said crank-arms, and stationary grooved guides engaged by said rollers and causing said feed-arms to be withdrawn from the chute, in a direction parallel to their length, when said shaft is 95 rotated; substantially as described.

3. In a baling-machine, a feeding or pressing device comprising, in combination with a curved chute, a plurality of prongs, a plate to which said prongs are slidingly secured, a transverse pivot for said plate, a cross-bar secured to said prongs, means for oscillating said cross-bar and prongs, and grooved guides for causing said prongs to feed the straw in only one direction, through said chute, substantially as described.

4. In a baling-machine, the combination, with a curved chute, of a plurality of prongs, a plate to which said prongs are slidingly secured, means for oscillating said plate, slots 110 in the chute through which said prongs extend, and curved plates secured to said plate, for keeping said slots closed except where said prongs enter; substantially as described.

5. In a baling-machine, the combination, 115 with a curved chute, of a plurality of prongs, slots into said chute through which said prongs oscillate, a cross-bar secured to said prongs, rollers on the ends of said cross-bar, stationary grooved cams for guiding said rollers, switch-blocks pivoted near the ends of said cams, and means for oscillating said prongs and cross-bar, whereby said prongs will feed the straw in only one direction through the chute, all substantially as described.

6. In a baling-machine, the combination, with a curved chute, having slots thereinto, of a plurality of prongs extending through said slots, a transverse pivot-shaft on which 130 said prongs are mounted, a cross-bar secured to said prongs, wrist-pins on the ends of said cross-bar, pitman-wheels having wrist-pins thereon, and pitmen mounted on said wrist-

pins, whereby said prongs are oscillated by the revolution of the wheels, substantially as described.

7. In a baling-machine, a bale-compressing device comprising a plurality of pressing-arms 100, a cross-bar 102 secured thereto, arms 103 secured to said cross-bar, a reciprocating plate 105 to which said arms are pivotally secured, and means for reciprocating said plate and oscillating said pressing-arms, comprising a rock-shaft 116, means for rocking the same, a lever 115 keyed thereon, a connecting-rod 114 connecting said lever with said cross-bar 102, a roller on the end of said cross-bar, and a stationary grooved guide 119 engaged by said roller and so formed as to cause said plate 105 to move in a direction opposite to that of said arms 100, while the bale is being compressed; substantially as described.

8. In a baling-machine, the combination, with a curved chute having longitudinal slots in its bottom, of a pivot-shaft 38, below the chute, a forked plate 43 mounted pivotally on said shaft, feeder-prongs 36 slidably connected to said plate in alinement with the slots in said chute, a cross-bar 44 secured to said prongs and provided with rollers on its ends, stationary grooved guides 46 engaged by said rollers, a pitman connected to said cross-bar, and a wheel for oscillating the pitman, substantially as described.

9. In a baling-machine, the combination, with a chute 25, of a set of oscillating and reciprocating feeder-prongs 36, and means for oscillating and reciprocating the same, comprising a cross-bar 44 having rollers on its ends, pitmen connected to said cross-bar, wheels for oscillating the pitmen, a grooved guide-cam 46, having a peripheral flange limiting the movements of said rollers, and pivoted switch-blocks 49 and 50, mounted within said flange, for causing said rollers to describe an approximately elliptical path and thereby reciprocate the prongs 36 as they oscillate, substantially as, and for the purpose, described.

10. In a baling-machine, the combination, with a feeding-chute having its bottom extending downwardly beyond its top and sides, of a bale-box normally registering with the lower end of the chute and communicating therewith; and means for swinging the bale-box from or toward the chute, said means comprising upwardly-extending hangers 64, 64' secured to a portion 58 of the top of the bale-box, inclined rods 67 to which said hangers are secured, a transverse lifter-bar 80 supporting said rods at their lower ends, pitmen 82 connected to said lifter-bar, and crank-shafts 84, and 85, for oscillating said lifting-bar, and said pitman; substantially as described.

11. In a baling-machine, the combination, with a feeding-chute having its bottom extending obliquely downward beyond its top and sides, of a bale-box normally resting

upon said bottom and opening into the chute, and means for raising the bale-box in a direction substantially parallel to that of the chute, said means comprising upwardly-extending hangers 64, 64' secured to the frame of the bale-box, sleeves at the upper ends of said hangers, straight rods 67 extending through said sleeves, said sleeves being slidably upon said rods, a rack rigidly secured to two of said hangers, parallel to said rods, a mutilated gear engaging said rack, and means for rotating said gear; substantially as described.

12. In a baling-machine, a bale-box comprising a pair of frame-plates 57, a pair of side plates 59, hinged to said frame-plates, respectively, and an end plate 61 also hinged to said frame-plates; and means for swinging said end plate and side plates outwardly to release a bound bale, and for returning said plates to normal position; said means comprising ears secured to said end and side plates respectively, a bar 69, links connecting said ears to said bar, a sleeve at the upper end of the bar, a rod extending through said sleeve and pivotally secured at one end, a transverse lifter-bar 79 secured to the opposite end of said rod, pitmen 83 connected to said lifter-bar, and cranked shafts 84, 85, for oscillating said pitmen and reciprocating said bar; substantially as described.

13. In a baling-machine, the combination, with a feeding-chute, of a bale-box embracing the lower end of the chute, the bale-box being moved along the chute by the pressure of the material to be baled, and means for regulating and retarding such movement; said means comprising a rack secured to the bale-box, a mutilated gear engaging the rack, a ratchet, keyed on the shaft of said gear, and a spring-pressed pawl engaging the ratchet; the whole operating substantially as described.

14. In a baling-machine, the combination, with a movable bale-box, of a transverse shaft, a gear-wheel or pinion secured on said shaft, a rack engaged by said gear for raising the bale-box and controlling its descent, a ratchet secured on said shaft, a pawl normally engaging said ratchet, a lever pivoted to said pawl and to a fixed support, a stop on said pawl, and a spring normally holding said stop against said lever, substantially as and for the purpose described.

15. In a baling-machine, the combination, with a movable bale-box, of a rack secured to said bale-box or its supports, a gear for reciprocating said rack, a shaft carrying said gear, a second gear secured on said shaft, and a mutilated gear for intermittently actuating said gear and thereby raising said bale-box, substantially as described.

16. In an automatic binding device for a baling-machine, a reciprocating wire-cutting bar, a lug on said bar, an oscillating lever engaging said lug, a slot in said lever, a crank-shaft playing in said slot, means for rotating

said crank-shaft, a stop for said cutter-bar, and a spring for drawing the cutter-bar against said stop, substantially as described.

17. In an automatic binding device for a baling-machine, a reciprocating wire-cutting bar, a lug on said bar, a slotted lever for engaging said lug, a plurality of rotatable retainer-disks, ratchets secured to said disks, a slotted lever pivoted near said disks and extending away therefrom, pawls pivoted on said lever for actuating said ratchets, and a shaft having cranked portions playing in the slots of said levers and thereby oscillating the levers, substantially as described.

18. In a gear-shifting device for a self-binding baling-machine, a rotatable shaft, a pinion secured on said shaft for driving a binding mechanism, a gear-wheel loosely mounted on said shaft, a roller secured to the face of said gear-wheel, an arm keyed to said shaft near said gear, a detent-arm pivoted to said arm, a detent on said detent-arm normally engaging said roller, an oscillating beam, the end of which, when depressed, engages the end of said detent-arm and releases said detent from said roller, and means actuated by said binding mechanism for tipping said beam so as to cause it to engage said detent-arm and thereby throw said binding mechanism out of gear with said shaft, substantially as described.

19. In a gear-shifting device for a self-binding baling-machine, the combination, with a baling mechanism, of a rotatable shaft, a pinion secured on said shaft for driving the feeding mechanism, a gear-wheel loosely mounted on said shaft, a roller secured to the face of said gear-wheel, an arm keyed to said shaft near said gear, a detent-arm pivoted to said arm, a detent on said detent-arm normally engaging said roller, an oscillating beam the end of which, when depressed, engages the

end of said detent-arm and releases said detent from said roller, and means actuated by the baling mechanism for tipping said beam 45 so as to cause it to engage said detent-arm and thereby throw said feeding mechanism out of gear with said shaft, substantially as described.

20. In a gear-shifting device for a self-binding baling-machine, the combination, with a binding mechanism, of a centrally-pivoted beam, a cranked shaft having its cranked portion oscillating longitudinally of said beam, a rod pivoted to said cranked portion, a 50 roller on the other end of said rod, said roller resting against said beam, a spring holding said roller against said beam, an arm secured to the axial portion of said cranked shaft, a catch for engaging said arm and oscillating 55 said crank-shaft, rod carrying said catch, and means, actuated by the binding mechanism, for oscillating or reciprocating said rod, substantially as, and for the purpose, described.

21. In a gear-shifting device for a self-binding baling-machine, the combination, with a baling mechanism, of a centrally-pivoted beam, a cranked shaft, having its cranked portion oscillating longitudinally of said beam, a rod pivoted to said cranked portion, 60 a roller on the other end of said rod, said roller resting against said beam, a spring holding said roller against said beam, an arm secured to the axial portion of said cranked shaft, a sleeve or opening in the lower end of 65 said arm, a rod passing through said sleeve or opening, and a collar secured on said rod for engaging said arm; said rod being reciprocated by the baling mechanism, substantially as and for the purpose described.
